DISPLAY PACKAGE OF FALSE EYELASHES AND ADHESIVE MATERIAL

D. Howard Aylott, 58-60 Bridge Road E.,
Welwyn Garden City, England

Filed July 2, 1968, Ser. No. 12,601

Term of patent 14 years

Int. Cl. D9—04

U.S. Cl. D9—185

FIG. 1.

FIG. 2.

FIG. 3.

FIG. 4.

FIG. 1 is a perspective view of a display package of false eyelashes and adhesive material showing my new design;

FIG. 2 is a rear elevational view thereof;

FIG. 3 is an end elevational view thereof; the opposite end being a mirror image of the end shown; and

FIG. 4 is a bottom plan view thereof.

I claim:

The ornamental design for a display package of false eyelashes and adhesive material, as shown and described,
